APPARATUS FOR BLEACHING PULP

Mathew F. McCombs and Francis W. Decker,
Niagara Falls, N. Y., assignors to Niagara Al-
kali Company, Niagara Falls, N. Y., a corpora-
tion of New York

Application September 5, 1935, Serial No. 39,353

3 Claims.

(Cl. 8-2)

This invention relates to apparatus for bleaching pulp; and it comprises bleaching apparatus having a shell formed with a frusto-conical top from which an outlet pipe emerges, and an out-
wardly dished bottom through which an inlet pipe extends into the upper portion of the shell for the discharge of pulp thereinto, after a chlorinating agent has been injected into the mass of pulp and preliminarily mixed with it by agitating means in the inlet pipe, an annular partition within the shell with a top of frusto-conical shape, overlying and enclosing the inlet pipe but spaced therefrom as well as from the top, sides and bottom of the shell, to direct the pulp after its up-
ward flow through the inlet pipe, downwardly to the bottom of the shell and thence again upwardly between the shell and partition to the outlet, means for injecting milk of lime or other neutralizing agent into the pulp in the outlet pipe, and an agitator in the outlet pipe beyond such in-
jector to agitate and intermix the injected milk of lime with the pulp so emerging from the ap-
paratus; all as more fully hereinafter set forth and as claimed.

In producing pulp, wood and woody fibers are chemically digested to dissolve lignin and leave cellulose. Some lignin is always left and the fiber must afterwards be bleached. With a far-
going digestion the resulting pulp usually has a weak fibrous structure. With less removal of lignin desirable fiber strength is obtained in the pulp but it is hard bleaching; it requires treatment with a considerable amount of chlorin. In treat-
ing hard bleaching pulp it is essential to prevent weakening of the fiber. It is a desideratum in the art to produce a strong hard bleaching pulp and then bleach it without sacrifice of strength.

In bleaching if the pulp is not uniformly ex-
posed to the chlorinating agent some parts are
apt to be excessively treated with other parts
undertreated. It is hard to secure uniform far-
going bleaching without any sacrifice of strength.

An object accomplished in this invention is providing apparatus for bleaching pulp under accurate control of bleaching conditions, thereby producing a pulp of uniform character and of good strength.

In securing this object the pulp to be bleached is passed alternately in reverse flow through apparatus in intermixture with an injected chlorinating agent to subject all parts of the pulp mass equally to chemical action while in continuous flow, and at the same time to permit accurate control of bleaching conditions. Apparatus is provided wherein chlorin is injected into a flowing stream of pulp and mechanically intermixed therewith by an agitator, before passing into a shell which is provided with a concentrically mounted partition for directing the flow of pulp in a tortuous stream therethrough, means

being also provided for injecting lime and water or other neutralizing agent into the so treated pulp as it emerges from the apparatus, together with mechanical agitating means beyond the in-
jector to assist the flow of pulp and aid in the thorough intermixture of milk of lime therewith.

Other and further objects will be apparent from the following description of drawing where-
in the single figure is a side view, partly in ver-
tical section, of apparatus embodying our inven- 10

A mass of pulp which is to undergo treatment flows in a continuous stream to the apparatus through inlet pipe 10 into which an injector pipe 11 extends for feeding a chlorinating agent there-
to, as for example chlorin gas from apparatus such as is shown in our copending application Serial No. 39,354, filed September 5, 1935, which provides for the continuous controlled flow of chlorin to such a process.

A mechanical agitator 12 of conventional de-
sign is mounted in the pipe 10 beyond the in-
jector 11 so that the pulp and chlorin are pre-
liminarily intermixed before entering the appa-
ratus now to be described.

The inlet pipe 10 has a vertical leg 13 which extends upwardly through the outwardly dished bottom 14 of a vertical shell 15 and terminates at a point in the upper portion of the shell. The shell 15 is mounted upon supports 16 and has a 30
valved discharge outlet 17 in its bottom.

An annular partition element 18 is mounted, as by spacers 19, within the shell to surround and enclose the vertical leg 13 of the inlet pipe, and such partition has a frusto-conical top 20 which 35 is spaced from the similarly shaped top 21 of the shell. The bottom of the annular partition terminates above the bottom of the shell and its frusto-conical top is formed with a small opening 22. Outlet pipe 23 communicates with in-
terior of the shell through its top and has a branch 24 into which an injection nozzle 25 extends. The inlet pipe and partition system define a pas-
sageway for the flowing pulp mass, of smooth 40 contour and of cross-sectional area progressively 45 increasing until the conical top 21 is reached. Restrictive openings are avoided; constrictions which might impede the flow of pulp. The pulp flows from the inlet to the outlet with a mini-
mum of frictional resistance against the appa-
ratus walls.

Milk of lime from the storage container 26 is forced by a pump 27 through piping 28 and 29 to the injection nozzle 25. The pipe 28 has a return 30 to the storage tank 26 so that excess 55 milk of lime not needed for the process will re-
turn to storage. The pump 27 therefore estab-
lishes a continuous circulation from and back to the storage tank; the excess milk of lime so circu-
lated being by-passed back to the tank while 60

such of it as is required for the process will flow through the branch pipe 29 to the injector nozzle 25. A gage 31 is provided in the pipe 29 for indicating the flow of milk of lime to the process through orifice 32 and such flow may be regulated according to requirements by a valve 33, also in piping 29.

The milk of lime may conveniently be drawn from a supply tank 34 which contains unscreened milk of lime by means of pump 35 and piping 36 into the storage tank 26 which, further, has a lime screen 37.

In the outlet pipe 23, beyond the injection nozzle 25, there is mounted an agitator 38 similar to the agitator 12 in the inlet. This device assists in the thorough mixing of the milk of lime and pulp passing from the apparatus through the pipe 23.

While not specifically shown in the drawing, the piping, shell and partition are advantageously all rubber covered to protect the metal from chemical action. Instead, any applicable corrosion-resistant varnish may be used.

From the foregoing it will be apparent that our apparatus provides for the thorough mixing of pulp in a bleaching process whereby all parts of its mass are subjected to the action of the bleaching agent so that accurate control of bleaching conditions is assured and a pulp of uniform character will result. The outer casing and inner partitions are so arranged that no short-circuiting or channeling of the flowing mass of pulp can occur; that is, the pulp-chlorin mixture must flow through the entire length of the tortuous path provided. This insures a steady flow of uniformly treated pulp. With the partition arrangement described it is not necessary to use a mechanical agitator. This is an advantage. Provision of pumps, impellers, etc. which will operate in the presence of corrosive liquids is a difficult problem. Ordinarily, it is most convenient to process a rather fluid pulp suspension, but the apparatus is well adapted for treatment of semi-fluid or plastic suspensions.

What we claim is:

1. Apparatus for bleaching pulp with chlorin and providing prolonged and intimate contact of chlorin and pulp, said apparatus comprising means for introducing chlorin at a controlled rate into a flowing mass of pulp, an agitator for causing intimate mixture of the pulp with the chlorin so introduced, a container shell, an unrestricted inlet pipe extending to the upper part of the shell and through which the pulp flows upwardly into the shell, a cylindrical partition within the shell and surrounding said inlet pipe, a frusto-conical top for said partition to direct the flowing pulp downwardly in the annular space between the partition and inlet pipe, said partition terminating above the bottom of the shell to provide an unrestricted passage for the pulp therearound whereby it will flow again upwardly between said partition and shell, said container shell, inlet pipe, partition and top being arranged to form an unrestricted progressively expanding passageway for the pulp, a frusto-conical top on said shell, an outlet pipe communicating with said top, means for injecting neutralizing agent into the mass of pulp emerging into the outlet pipe and a mechanical agitator for causing intimate mixture of the pulp

and neutralizing agent and for assisting in moving the pulp through said outlet pipe.

2. Apparatus for bleaching pulp with chlorin and providing prolonged and intimate contact of chlorin and pulp, said apparatus comprising a container shell having an outwardly dished bottom and a frusto-conical top, an unrestricted inlet pipe for pulp extending through said bottom and terminating in the upper portion of said shell, an outlet pipe from the upper frusto-conical top thereof, an annular partition mounted within said shell and having a frusto-conical top, the lower end of said partition being spaced above the bottom of said shell, said partition surrounding the inlet pipe, thereby to direct the flow of pulp, after its upward passage through the inlet pipe, downwardly between said pipe and partition, and thence again upwardly between the partition and shell to the outlet, said container shell, inlet pipe, partition and partition top being so constructed and arranged as to form an unrestricted progressively expanding passageway for the pulp, together with means for injecting chlorin into the pulp mass before entering said shell, and means for injecting neutralizing agent into the so treated pulp mass emerging from said shell, the inlet pipe being so constructed and arranged as to maintain the shell full of pulp during operation.

3. Apparatus for bleaching pulp with chlorin and providing long and intimate contact of chlorin and pulp, said apparatus comprising a cylindrical shell having an outwardly dished bottom and a frusto-conical upper end, an unrestricted inlet pipe for pulp extending from a level above the top of the shell, downward below the shell, upwardly through said bottom and upwardly into the shell coaxial therewith, whereby the shell is maintained full of pulp during operation, an outlet pipe in communication with the shell at the top of its frusto-conical end, a cylindrical partition suspended within said shell and having a frusto-conical top, the lower end of said partition being spaced above the bottom of said shell, spacing means for suspending the said partition equidistant from the walls and top of said shell without imposing any substantial restriction of the space between partition and shell, the said upwardly projecting inlet pipe extending into the chamber defined by said partition and terminating in the plane of the base of the frusto-conical top thereof, said inlet pipe, partition, partition top, shell and shell bottom being so constructed and arranged as to provide an unrestricted progressively expanding passageway for the pulp, means for injecting measured quantities of chlorin into the mass of pulp in said inlet pipe, a mechanical agitator in said pipe for causing intermixing of chlorin with the pulp prior to its entry into the said shell and for assisting its flow therethrough upwardly through said inlet pipe, thence downwardly between said inlet pipe and annular partition, and again upwardly between said partition and the shell to the outlet pipe, together with means for injecting neutralizing agent into the pulp emerging from said shell, and an agitator in said outlet pipe therebeyond for causing intimate mixture of such neutralizing agent with the pulp and for assisting flow of pulp through the outlet pipe.

MATHEW F. MCCOMBS.
